(57) **CLAIM**

The ornamental design for an external enclosure portion of
a removable expansion card, as shown and described.

DESCRIPTION

FIG. 1 is a front perspective view of a first embodiment of
an external enclosure portion of a removable expansion card,
according to our new design shown on an enlarged scale;

FIG. 2 is a right side view of the first embodiment;

FIG. 3 is a rear view of the first embodiment;

FIG. 4 is a bottom view of the first embodiment;

FIG. 5 is a left view of the first embodiment;

FIG. 6 is a top view of the first embodiment;

FIG. 7 is a front view of the first embodiment;

FIG. 8 is a front perspective view of a second embodiment
of an external enclosure portion of a removable expansion
card according to our new design shown on an enlarged
scale;

FIG. 9 is a right side view of the second embodiment;

FIG. 10 is a rear view of the second embodiment;

FIG. 11 is a bottom view of the second embodiment;

FIG. 12 is a left view of the second embodiment;

FIG. 13 is a top view of the second embodiment; and,

FIG. 14 is a front view of the second embodiment.

The broken line portions in the drawings are for illustrative
purposes only and form no part of the claimed design.
